PROCESS FOR ACTIVATING PROVITAMINS

Benjamin Kramer, Samuel Natelson, and Albert E. Sobel, Brooklyn, N. Y.

Application March 19, 1936, Serial No. 69,736

9 Claims. (Cl. 204—31)

This invention relates to antirachitic vitamins and, more particularly, relates to novel apparatus for and methods of converting provitamins into antirachitic vitamins.

Heretofore, several methods have been proposed and used to antirachitically activate foods and sterols having no antirachitic potency. The most widely accepted process for antirachitically activating substances comprises exposure to a source of ultra-violet light. Commercial production by such a process requires an expensive investment in materials, particularly quartz. A quartz mercury arc lamp is used to generate ultra-violet rays which are directed upon the substance in a solid state or, more generally, in a suitable liquid solution contained in quartz flasks or the like.

Production of ultra-violet light by sources other than a mercury arc lamp, such as the glow discharge, open arc discharges or the corona discharge are relatively inefficient. Exposure of provitamins to open arc or corona discharges results in the destruction of the vitamin almost as rapidly as it is formed. The other proposed methods for antirachitically activating provitamins are of mere laboratory significance on account of the very low efficiencies of conversion together with the expensive apparatus and the skilled manipulation required. These methods include: exposure of the material to X rays; bombardment of the material by electrons in a cathode ray tube; subjection of the material to a high frequency alternating current greater than a thousand cycles.

We have discovered a simple, inexpensive and very efficient method of antirachitically activating provitamins by an electric discharge. By an extended investigation of the action of the different types of electrical discharges through gases upon provitamins, we have discovered that by carefully controlling the various parameters, a critical condition exists whereby the conversion of provitamins to antirachitic vitamins is extremely favorable. The critical electrical discharge, generally referred to as the brush discharge, performs the efficient antirachitic conversion. We have found that for a particular physical apparatus, a most favorable voltage exists, dependent upon the spacing of the electrodes between which the material is placed and that a most suitable frequency of application of the alternating current exists of the order of 250-350 cycles. As will be explained in more detail hereinafter, a voltage below the critical for a particular frequency, area and spacing of the plates and dielectric will produce a glow discharge instead of a brush discharge and the

antirachitic vitamin yield will be materially diminished. On the other hand, improper application of too high a potential for that frequency etc. may result in a spark discharge which will destroy the provitamins. Application of frequencies below or above the critical range also reduces the efficiency of antirachitic conversion of the provitamins.

We have found that the most economical production of substances containing antirachitic vitamins is to activate ergosterol or crude cholesterol and subsequently introduce a small percentage of the activated sterols to foods and medicines, for example yeast, olive oil, milk, cod liver oil and the like. The ergosterol or crude cholesterol is applied between the electrodes of the apparatus according to our present invention, preferably in a solid, loosely powdered state. In another form of our invention, the sterols or provitamin is dissolved in a suitable solvent as, for example, ether and introduced between the discharge electrodes in a fine spray.

We have found that the process according to our present invention also has a sterilizing effect upon the foods or substances subjected to it in that bacteria, protozoa and other micro-organisms are destroyed. Foods which possess antirachitic properties in a greater or less degree, such as milk, olive oil, yeast, cod liver oil and the like, may be directly activated by the brush discharge apparatus of our present invention.

Accordingly, an object of our invention is to provide novel methods of converting provitamins into antirachitic vitamins.

Another object of our invention is to convert provitamins into antirachitic vitamins by a brush discharge.

A further object of our invention is to provide simple, inexpensive and efficient apparatus for and methods of converting provitamins such as sterols into antirachitic vitamins.

Still a further object of our invention is to provide novel apparatus for and methods of sterilizing food substances.

These and other objects of our invention will be evident in the following description in connection with the drawing, in which:

Figure 1 is a schematic diagram used in the description of electric discharge phenomena through gases.

Figure 2 is a qualitative, graphical representation of the several gaseous electric discharge phenomena.

Figure 3 is a modification of Figure 1.

55

Figure 4 is a partial perspective illustration of a preferred embodiment of our present invention.

Figure 5 is a qualitative curve representing the efficiency of conversion of provitamins to anti-rachitic vitamins with respect to the frequency of the applied alternating current potential.

When a voltage is applied between two spaced conductors having a gaseous atmosphere between, a number of distinct types of electrical discharges may take place between the plates through the gas dependent upon the nature and magnitude of the potential applied to these plates. A variety of phenomena accompanies gaseous electrical discharges including luminous, thermal, magnetic, 15 mechanical and chemical effects in varying degrees. In accordance with our present invention, the chemical action of the electrical discharge is utilized and the conditions of operation are adjusted so as to produce the type of discharge having a maximum chemical action and a minimum of the other physical actions. This type of electrical discharge is known as the brush discharge. In order to clearly set forth the critical parameters for optimum antirachitic conversion of the 20 materials, the following discussion as to the several types of electrical discharge is presented.

Referring to Figure 1, two metallic plates 10 and 11 are spaced from each other by a fixed amount, for example, one centimeter. The space 12 between electrodes 10 and 11 contains a gaseous atmosphere for example ordinary air at atmospheric pressure. A variable high potential or voltage source 13 is connected to plates 10 and 11 by corresponding conductors 14 and 15.

An ammeter 16 may be inserted in series with conductor 15 for observation of the current flowing during an electrical discharge between plates 10 and 11.

Figure 2 is a graph representing the variation in the current of the discharge as indicated on ammeter 16 as plotted with respect to the variable voltage applied between electrodes 10 and 11 with a fixed spacing. At low voltages, for example below one thousand volts, practically no current will flow between the electrodes. As the voltage between the plates 10 and 11 is slowly increased, minute current will flow between them as represented by curve 17. The discharge 17 is characteristically non-luminous or invisible and is accompanied by negligible chemical or other physical effects. At a certain region 18 which is definite for given conditions of temperature, pressure and electrode spacing the glow discharge begins which represents a discontinuity in the graph. Curve 19 represents the voltage-current relation of the glow discharge. The voltage may be increased to a very high value and the glow discharge will still be maintained and the current will correspondingly increase. The glow discharge is accompanied by a characteristic luminosity which includes ultra-violet light.

As the voltage is further increased, it will reach a peak value e_0 which is practically the maximum voltage which the electrodes 10-11 can support for a particular gaseous atmosphere and spacing. The glow discharge disappears at the region 20 and the characteristic brush discharge occurs. The brush discharge has sometimes also been called the silent discharge or the dark discharge. These terms are misnomers since the brush discharge is neither silent nor dark for it is attended by a peculiar sound and by some light.

By the term "brush discharge" as used herein-after in the specification and claims, we refer to the electrical discharge produced across a region

by a voltage gradient which corresponds to substantially the maximum voltage which can be supported between the electrodes bounding the region, other conditions remaining the same. We further distinguish the "brush discharge" as the electrical discharge occurring after the glow discharge, on increasing the voltage, and corresponds to the region characterized by the curve portion 20 of Figure 2. The brush discharge corresponds in Figure 2 to the discharge produced in the vicinity of the peak voltage e_0 . Other conditions which affect the particular "brush discharge voltage" for carrying out our process are the frequency of the applied voltage, the spacing of the bounding electrodes, the character of dielectric material used and the gaseous condition within the discharge region.

The brush discharge is maintained by careful adjustment of the voltage for a given structure. Increasing the electrical energy or current supply to the electrodes causes the production of the spark discharge represented by region 21. Region 22 represents the electric flame which results from further increasing the current supply. Curve 23 represents the negative voltage-current characteristic of the high tension arc and region 24 represents the low tension arc as is well known by those skilled in the art. It is to be understood that the graph plotted in Figure 2 is merely a qualitative representation of the several types of electrical discharge phenomena and that the actual voltage and current depend upon the type, surface area and shape of the oppositely disposed electrodes, the spacing between said electrodes, the type of gas and its temperature and pressure as contained between the electrodes. The type of voltage which produces the electrical discharge characteristics represented in Figure 2 may be an interrupted direct current or an alternating current voltage. The frequency of the interruptions or alternations of the voltage source should be relatively low, for example, below a thousand cycles, otherwise different electrical actions will occur. As the frequency of the voltage source is increased, the peak voltage supported, corresponding to e_0 of Figure 2, will be lowered. An increase in frequency will increase the current flow between the electrodes 10-11 due to a capacitative or reactive current flow due to the function of the plates 10-11 as an electrical condenser.

The phenomena of the electrical discharge becomes more complicated than the relatively simple representation of Figure 2 when dielectric material is interposed between the electrodes 10-11. Referring to Figure 3, a glass plate 25 is placed adjacent to the inner surface of electrode 10 and another glass plate 26 at the inner surface of plate 11. A variable high potential alternating current source 27 is applied to the conductors 14-15. If the generator 27 is operated at two hundred cycles and the voltage applied to the electrodes 10 and 11 is increased until the brush discharge corresponding to curve 20 in Figure 2 occurs, it will be found that the brush discharge will occur when the electrodes 10 and 11 are closer together than the corresponding case where no dielectric plates 25-26 are used. If the plates 10 and 11 of Figure 3 are separated a distance equal to that described in connection with Figure 1, namely one centimeter, then the maximum voltage corresponding to e_0 of Figure 2 will be greater at the brush discharge. The higher voltage is due to the presence of the dielectric material, namely the glass plates 25-26 interposed be-

between the electrodes 10 and 11 which act to reduce the potential gradient through the atmosphere as is well known in the art. However, it is evident that a brush discharge may be produced between two electrodes as long as a gaseous atmosphere exists between them, and that it is difficult to express the value of the voltage to be applied for all conditions. If the frequency of generator 27 is increased, the maximum voltage which a given discharge structure can support will be lessened.

The critical spacing of the electrodes may be determined for a particular voltage and frequency supply as follows: The electrodes 10 and 11, with the dielectric materials 25 and 26 in place (Fig. 3) if required, are connected to the supply and are gradually brought together until the easily recognizable spark discharge begins. The electrodes are then slowly moved apart until the spark discharge just disappears. The brush discharge will then be evident to those skilled in the art.

We have discovered that provitamins placed in the electrostatic field within a brush discharge are efficiently converted into antirachitic vitamins. We have also found that the antirachitic conversion is relatively insignificant for electrical discharges occurring at the lower voltages, namely the non-luminous discharge represented by curve 17 in Figure 2 and the glow discharge represented by curve 19; and that the discharges occurring beyond the brush discharge, namely the spark discharge and the electric arc discharges represented by curves 21, 22, 23 and 24 of Figure 2 actually destroy the provitamins. It is to be understood that the brush discharge represents an electrochemical conversion of the provitamin to the antirachitic vitamin. This electrochemical action is analogous to the production of ozone which has also been found to be most efficient in the brush discharge region.

In a preferred embodiment for carrying out the process of our present invention, we utilize two concentric glass tubes provided with metal foil electrodes as illustrated in Figure 4. An outer cylindrical glass tube 28 is provided with a metallic plate or foil electrode 29 attached to its outer surface. The inner concentric glass tube 30 is coated with a metallic sheet or foil electrode 30 upon its inner surface. The annular distance between concentric tubes 28 and 30 is optional and determines the volume capacity of the apparatus. The metallic electrodes 29 and 31 are connected to a suitable alternating current voltage source 32 by conductors 33-34.

Ergosterol 35 or other suitable provitamin material is placed between the glass cylinders 28 and 30. If a solid state of the substance is used, it should be in a loosely powdered form. The value of the voltage from electric source 32 applied between electrodes 29 and 31 is predetermined so as to produce a brush discharge therebetween. One must be careful that the voltage applied to the apparatus produces the true brush discharge corresponding to curve 20 of Figure 2. If the current is too low, the inefficient glow discharge represented by curve 19 will take place; if the current is too high, a spark discharge represented by curve 21 will take place and destroy any vitamins that might be formed. In a particular example, glass cylinders 28 and 30 of one millimeter thickness and with an annular space of two millimeters required a voltage of the order of 8000 volts to produce a brush discharge.

We have found that it is necessary to place the provitamin substance 35 in the electrostatic field

within the actual brush discharge for antirachitic conversion. Experiments have shown that if the provitamin substance 35 be placed at the outer regions of the annular space, namely the regions 36 and 37 immediately outside of the direct electrostatic field, negligible antirachitic vitamin conversion results, demonstrating absence of ultra violet light conversion.

An important feature of our present invention resides in the use of a critical frequency for the most efficient antirachitic conversion of the provitamin substance. We have discovered that for most provitamin substances, particularly the sterols, the optimum frequency range of conversion occurs between 250 and 350 cycles. The efficiency of conversion decreases with frequencies below 250 cycles, as well as for frequencies above 350 cycles. Figure 5 is a qualitative curve representation 38 of the relative conversion of provitamin substances to antirachitic vitamins plotted with respect to the frequency of the applied potential in cycles per second.

It is to be understood that a brush discharge occurs along the points of curve 38 for the various frequencies plotted. At zero frequency a relatively very small yield occurs. As the frequency is increased to 250 cycles, the yield correspondingly increases until the maximum. As the frequency is further increased to about 350 cycles, the efficiency of conversion continues near the maximum. For particular substances, a peaked nature of curve 38 will be evident at a single critical frequency in the order of 250-350 cycles. However, in Figure 5, we have not attempted to accurately represent any particular case but rather to give an approximate conception of the effect and range of the frequency of the voltage generator 32 upon the efficiency of conversion. For frequencies of the applied voltage to produce the brush discharge above 350 cycles, the efficiency of conversion diminishes until at 1000 cycles and above, the efficiency is relatively small.

As seen by curve 38 of Figure 5 approximately 50% of the maximum efficiency or yield occurs with frequencies in the range of 150 to 550 cycles per second. By choosing the intermediate frequency range of 250 to 350 cycles per second the maximum efficiency or yield is approached. For most provitamin substances a frequency of about 300 cycles per second will produce best results.

It is necessary for a gaseous atmosphere to prevail between the discharge electrodes, therefore the solid provitamin 35 should be in a loosely powdered state. When air is used, ozone is formed during the activation process according to our invention. Ozone or the action of the oxygen itself acts to slowly decompose the vitamins and accordingly somewhat reduce the yield. We have found that if the activation process between the concentric tubes 28 and 30 is carried on in the presence of an inert gas such as nitrogen the efficiency of conversion is materially increased. Nitrogen may either be continuously passed through the substance 35 being activated in the annular chamber or may be confined to the annular chamber if it is made gas tight as will be understood by those skilled in the art. No activation is observed if a solution of provitamin fills the annular space, since a brush discharge cannot be established thru the solvent.

A modification for activating the ergosterol or other provitamin resides in continuously spraying it in the form of a fine dust between the annular space of a relatively long structure. The

ergosterol, crude cholesterol or other provitamin substance may be dissolved in a suitable solvent such as ether or alcohol and passed through the brush discharge in the annular space in the form of a fine spray. Antirachitic conversion of provitamins to vitamins is evident with an exposure as low as two minutes. Increasing the time of exposure to a predetermined maximum of the provitamin substance will increase the yield. Exposure of a half hour will in most cases give a maximum yield consistent with commercial production. However, we do not restrict our process to the time of exposure which depends upon the shape and size of the apparatus as well as the type and form of provitamin substance being activated.

Another important factor for increasing the efficiency of conversion is the temperature at which the conversion takes place. It is preferable to carry out the process at a temperature of about 0° C. although good results will be obtained at ordinary room temperatures. The temperature of the whole apparatus, and therefore of the substance 35 being converted, may be maintained cool by means of a fan directly blowing thereon or preferably by the continuous circulation of cooling water through the central circular tube 30 of the apparatus. Other suitable forms of cooling will also be evident to those skilled in the art. 30 The true nature of the electro-chemical action during the brush discharge has been in controversy for some time in the art. However, in the present case, the activation appears to be due to the impingement of ions or activated atoms or 35 molecules produced within the brush discharge from the gaseous dielectric, upon the provitamin substance which release their energy to the provitamin, converting it to the antirachitic vitamin.

The important factors for the production of 40 antirachitic vitamins from provitamins are the production of a brush discharge; placing a provitamin substance such as ergosterol or crude cholesterol within the brush discharge preferably insulated from the metallic electrodes by glass plates or the like; using a loosely powdered provitamin substance structure, or in the form of fine dust spray, or a spray of a solution of provitamin substance through the brush discharge; 45 preferably maintaining an inert gaseous atmosphere such as nitrogen and keeping the substance cool preferably at 0° C. The production of the brush discharge should be determined for each particular structure designed. The necessary voltage is determined by the shape of the electrodes, their size and their spacing. The frequency of the applied voltage should preferably be in a most efficient range for conversion, generally within 250 and 350 cycles. A suitable source of the high voltage alternating current 50 necessary for carrying out our process will be evident to those skilled in the art. An alternating current generator connected to a step-up transformer will provide the necessary high voltage. The alternator is adjusted to the proper 55 optimum frequency. For small quantity production, an induction coil adjusted to, for example, 250 cycles of interruption, may be used to maintain the brush discharge in an apparatus constructed to operate with the voltages, for example 60 8000 volts, presented at the output thereof.

A convenient way of producing the desired frequency and voltages is to generate the frequency by one of the usual types of variable audio oscillators, to amplify this by means of the standard types of pre-amplifiers and amplifiers and to

feed this into a transformer designed to raise the voltage to the desired range. A condenser board is used in connection with the final transformer so as to keep the current and voltage in phase.

The ergosterol or crude cholesterol is a concentrated antirachitic vitamin source. It is too potent for direct consumption. Small amounts are administered or eaten, preferably in combination with a food or medicine. A small percentage of the activated material is mixed with cod liver oil, yeast, milk or other edible substance. No change in taste or odor of the food occurs. The antirachitic potency of the edible material treated in this manner is equivalent to direct activation thereof. It is much more economical to produce edible or medicinal antirachitic substances by adding a small percentage of concentrated antirachitic vitamin content material to the substances, as compared to direct activation thereof. It is to be understood that antirachitically potent substances may be directly activated in accordance with our present invention.

This application is a continuation in part of our application Serial No. 723,314, filed May 1, 1934.

We claim:

1. The process for antirachitically activating provitamins which comprises introducing provitamin material into a gaseous region and applying a voltage gradient across the gaseous region 30 containing the provitamin material for producing a gaseous brush discharge about the provitamin material, whereby the provitamins are converted into antirachitic vitamins by the brush discharge acting on the provitamin material in the gaseous 35 atmosphere.

2. The process for antirachitically activating provitamins which comprises introducing provitamin particles into a gaseous region and applying a voltage gradient across the gaseous region 40 containing the provitamin particles for producing a gaseous brush discharge about the provitamin particles, whereby the provitamins are converted into antirachitic vitamins by the interrupted brush discharge acting on the provitamin particles in the gaseous region, and cooling the discharge region to about 0° centigrade to increase the efficiency of conversion.

3. The process for antirachitically activating provitamins which comprises introducing provitamin material in a powdered and loosely packed form into a gaseous region and applying a voltage gradient across the gaseous region containing the provitamin powder at substantially the maximum voltage which the region can support for producing a gaseous brush discharge about the provitamin material, whereby the provitamins are converted into antirachitic vitamins by the brush discharge acting on the provitamin material in the gaseous atmosphere.

4. The process for antirachitically activating provitamins which comprises continuously passing a solution of provitamin material as a fine spray through a gaseous region and applying a voltage gradient across the gaseous region containing the provitamin spray at substantially the maximum voltage which the region can support for producing a gaseous brush discharge about the provitamin material, whereby the provitamins are converted into antirachitic vitamins by the brush discharge acting on the provitamin material.

5. The process for antirachitically activating provitamins which comprises introducing provitamin material into an inert gaseous region and

- applying a voltage gradient across the gaseous region containing the provitamin material at substantially the maximum voltage which the region can support for producing a gaseous brush discharge about the provitamin material, whereby the provitamins are converted into antirachitic vitamins by the brush discharge acting on the provitamin material in the inert gaseous atmosphere.
5. The process for antirachitically activating provitamins which comprises introducing provitamin particles into a region of nitrogen gas and applying a voltage gradient across the gaseous region containing the provitamin particles at substantially the maximum voltage which the region can support for producing a gaseous brush discharge about the individual provitamin particles, whereby the provitamins are converted into antirachitic vitamins by the brush discharge acting on the provitamin particles in the nitrogen atmosphere.
10. 6. The process for antirachitically activating provitamins which comprises introducing provitamin material into a gaseous region and applying a voltage gradient across the gaseous region containing the provitamin material for producing a gaseous brush discharge about the provitamin material, and generating the brush discharge with an interrupted current having about 300 interruptions per second, whereby the provitamins are converted into antirachitic vitamins by the interrupted brush discharge acting on the provitamin material in the gaseous atmosphere.
15. 7. The process of antirachitically activating provitamins which comprises introducing provitamin material into a gaseous region and applying a voltage gradient across the gaseous region containing the provitamin material for producing a gaseous brush discharge about the provitamin material, and generating the brush discharge with an alternating voltage having a frequency of about 300 cycles per second, whereby the provitamins are converted into antirachitic vitamins by the brush discharge acting on the provitamin material in the gaseous atmosphere.
20. 8. The process of antirachitically activating provitamins which comprises introducing provitamin particles into a gaseous region and applying a voltage gradient across the gaseous region containing the provitamin particles at substantially the maximum voltage which the region can support for producing a gaseous brush discharge about the individual provitamin particles, and generating the brush discharge with an alternating voltage having a frequency in the range of 150 to 550 cycles per second, whereby the provitamins are converted into antirachitic vitamins by the alternating brush discharge acting on the provitamin particles in the gaseous atmosphere.
25. 9. The process for antirachitically activating provitamins which comprises introducing provitamin particles into a gaseous region and applying a voltage gradient across the gaseous region containing the provitamin particles at substantially the maximum voltage which the region can support for producing a gaseous brush discharge about the individual provitamin particles, and generating the brush discharge with an alternating voltage having a frequency in the range of 150 to 550 cycles per second, whereby the provitamins are converted into antirachitic vitamins by the alternating brush discharge acting on the provitamin particles in the gaseous atmosphere.
